Charles W. Gray Inventor

By G. L. Tracy atty.

UNITED STATES PATENT OFFICE.

CHARLES W. GRAY, OF CHATTANOOGA, TENNESSEE.

STAMPING-MACHINE.

No. 845,776.

Specification of Letters Patent.

Patented March 5, 1907.

Application filed November 13, 1905. Serial No. 287,043.

To all whom it may concern:

Be it known that I, CHARLES W. GRAY, a citizen of the United States, residing at Chattanooga, in the county of Hamilton and State of Tennessee, have invented a certain new and useful Improvement in Stamping-Machines, of which the following is a full, clear, concise, and exact description, reference being had to the accompanying drawings, forming a part of this specification.

My invention relates to machines for sealing envelopes and applying postage-stamps thereto, and has for its general object the provision of a machine of an improved construction and design that will very effectively operate to perform these functions.

More specifically, my invention has for one of its objects the provision of a machine of the class described whereby envelopes may effectively be sealed, notwithstanding the bulk of their contents, within the range of the mechanism and the stamps effectively applied thereto. To this end I employ a rocking lever, that is preferably manually operated, the rocking lever being operatively associated with a stamping-plate and a sealing-plate a spring being employed to place the operating-lever in its normal position. The stamping-plate is located below the sealing-plate and has separable operative connection with the operating-lever, the stamping-plate being desirably supported upon an intermediately-pivoted member, with which said rocking lever has separable driving connection, preferably through the agency of a rod extending vertically from said member toward the lever. The stamp-applying plate and the plate for sealing the envelopes move in opposite directions, to which end a supporting-plate for the envelopes to be sealed and stamped is interposed

between the same, the stamp-applying plate desirably working through an opening in this supporting-plate, so that as the hand-lever is rotated the envelop-sealing plate is moved downward toward said foundation-plate, and the stamp-applying plate is moved upward through an opening in said foundation-plate. This opening in the foundation-plate may, with the stamp-applying plate moving therein, constitute a magazine for the stamps, and in order that the stamps may be applied and the envelopes sealed the flaps of the envelopes and the por-

tions of the envelopes that are to receive the stamps are moistened through the agency of any suitable moistener, whereafter the envelop is interposed between the sealing-plate and the stamp-affixing plate and the lever operated to stamp and seal the interposed envelop.

The sealing-plate has driving connection with the operating - handle, preferably through the agency of a compressible plunger, this compressible plunger being desirably formed of two sections, one section being rigid and the other being spring-like. In this way the sealing-plate may be firmly pressed upon the foundation-plate, and the subsequent operation of the stamping-plate may be effected after the sealing-plate has been thus brought to the foundation-plate, for the spring portion of the plunger will permit sufficient pressure to be exerted upon the sealing-plate and at the same time will permit the continued depression of the operating-lever to force the elevation of the stamping-plate through the foundation-plate.

I will explain my invention more fully by reference to the accompanying drawing, in which—

Figure 1 is a rear elevation of the preferred embodiment of my invention, certain parts being broken away more clearly to reveal details of construction. Fig. 2 is a plan view thereof. Fig. 3 is a sectional view showing the sectional formation of the operating-plunger, which is preferably at the upper part of the plunger, and the association of this plunger with the operating-handle, the view being taken at right angles to the direction in which Fig. 1 is taken.

Like parts are indicated by similar characters of reference throughout the different figures.

The foundation-plate 1, that I have hitherto spoken of, constitutes the top of a bottomless box that contains the stamp-applying mechanism. This foundation-plate has an opening 2, which is desirably flanged at 2' to afford a space in which postage-stamps may be received. In this space 2 there is a movable plate 3, that constitutes the bottom of a magazine that is thus established for the stamps. The plate 3 is preferably provided with depending flanges 4, that form, with the bottom of the plate, a spring-barrel, in which a spring 5 is contained, this spring 5 engag-

ing an intermediately-pivoted lever 6, said lever having its mounting in the side walls of the box containing the stamp-aligning mechanism. The spring 5 preferably does not directly engage the lever 6; but said spring desirably engages the bottom of a cylindrical section 6', which telescopes into the spring-barrel constituted of the stamping-plate and the flanges 4. The end of the lever 6 opposite that engaging the spring 5 is preferably engaged by a plunger-pin 7, which is operated by the mechanism hereafter to be set forth, to effect a vertical movement of the elements 3, 4, 5, and 6', whereby the top-most stamp in the stamp-magazine may be applied to an envelop.

In order that the stamp may be applied and the envelop at the same time sealed, there is provided a sealing-plate 8, to which 20 an upwardly-extending operating-plunger is connected. This operating-plunger includes a reduced portion 9, that passes through a barrel 10, provided in the stationary support 11, that is rigidly secured to the foundation-plate 1, a spring 12 within the barrel 10 engaging the enlarged portion 13 of the plunger normally to lift the plunger and the sealing-plate 8, which is united with a rod 14, the latter rod being fastened to the lower end of 25 the part 9 of the plunger that projects through the support 11. The plate 8 is somewhat loosely fastened to the rod 14, so that envelops and their contents of uneven thickness may readily be sealed and stamped. 30 The plunger 9 13, also includes a section formed of the spring 15, which engages at its bottom the top of the portion 13, the top of the spring engaging the housing 16, that maintains the spring in position and affords a 35 convenient means for effecting the driving connection between the operating handled swinging lever 17 and the plunger. The housing 16 desirably carries a roller 18, with which the lever 17 is desirably directly engaged, so as to prevent wear between the lever and the housing 15. In order that the 40 housing 15 may be confined to a vertical line of travel, a vertical slot 18' is formed in the element 13, that engages the inner smooth 45 end of the screw 19, that holds the roller 18 in position.

The plunger-pin 7 lies within the plane of movement of the lever 17 and is desirably of such a length that it is not engaged by the 50 lever until the sealing-plate has been moved substantially into contact with the plate 1, (there being then no envelop between the stamping and sealing plates,) whereafter said pin 7 is depressed to effect the elevation of 55 the stamping-plate, there being sufficient yield in the spring 15 to permit of the full elevation of the stamping-plate to effect the application of the stamp while the envelop is being sealed, the spring 5 being sufficiently 60 strong to transmit force from the pin 7 to ap-

ply each stamp in the magazine as the envelops are inserted, even though it be the last stamp. In the construction shown the stamping-plate is released before the sealing-plate is elevated, so that none of the stamps are likely to be displaced from the stamp-magazine.

It is obvious that changes may readily be made without departing from the spirit of my invention, and I do not, therefore, wish to be limited to the precise construction shown; but,

Having thus described my invention, I claim as new, and desire to secure by Letters Patent, the following:

1. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, and mechanism whereby the stamping-plate may be actuated by said operating-lever, the spring-section of the plunger permitting continuation of the operation of the lever to effect movement of the stamping-plate subsequent to a movement of the sealing-plate.

2. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, and mechanism whereby the stamping-plate may be actuated by said operating-lever, the spring-section of the plunger permitting continuation of the operation of the lever to effect movement of the stamping-plate subsequent to a movement of the sealing-plate, the mechanism that affords the connection between said operating-lever and the stamping-plate permitting separable driving connection between the operating-lever and the stamping-plate.

3. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its

formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, said mechanism including a pin disposed in the plane of movement of the lever, a rocking lever engaging the pin, and a spring affording connection between the stamping-plate and the rocking lever.

4. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, the mechanism that affords the connection between said operating-lever and the stamping-plate permitting separable driving connection between the operating-lever and the stamping-plate, said mechanism including a pin disposed in the plane of movement of the lever, a rocking lever engaging the pin, and a spring affording connection between the stamping-plate and the rocking lever.

40 5. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, and a spring effecting the elevation of the sealing-plate when the lever is relieved of operating influence.

60 6. An envelop sealing and stamping machine, including a foundation-plate, a sealing-plate movable toward and from said foundation-plate, a stamping-plate movable toward and from the sealing-plate, the envelop to be sealed and stamped being interposed be-

tween the sealing-plate on one side and the foundation and stamping plates on the other side, a plunger connected with the sealing-plate and including a spring in its formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, the mechanism that affords the connection between said operating-lever and the stamping-plate permitting separable driving connection between the operating-lever and the stamping-plate, and a spring effecting the elevation of the sealing-plate when the lever is relieved of operating influence.

7. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, said mechanism including a pin disposed in the plane of movement of the lever, a rocking lever engaging the pin, a spring affording connection between the stamping-plate and the rocking lever, and a spring effecting the elevation of the sealing-plate when the lever is relieved of operating influence.

8. An envelop sealing and stamping machine, including a foundation-plate, a sealing-plate movable toward and from said foundation-plate, a stamping-plate movable toward and from the sealing-plate, the envelop to be sealed and stamped being interposed between the sealing-plate on one side and the foundation and stamping plates on the other side, a plunger connected with the sealing-plate and including a spring in its formation, an operating-lever engaging the plunger, mechanism whereby the stamping-plate may be actuated by said operating-lever, the spring-section of the plunger permitting continuation of the operation of the lever to effect movement of the stamping-plate subsequent to a movement of the sealing-plate, the mechanism that affords the connection between said operating-lever and the stamping-plate permitting separable driving connection between the operating-lever and the stamping-plate, said mechanism including a pin disposed in the plane of movement of the lever,

a rocking lever engaging the pin, a spring affording connection between the stamping-plate and the rocking lever, and a spring effecting the elevation of the sealing-plate when the lever is relieved of operating influence.

In witness whereof I hereunto subscribe

my name this 7th day of November, A. D. 1905.

CHARLES W. GRAY.
